A. J. BROOKINS

GOVERNOR FOR AUTOMATIC CONTROL APPARATUS FOR RAILROADS

Filed Sept. 1, 1922

ANDREW J. BROOKINS,
INVENTOR.

BY Charles Turner Brown,
ATTORNEY.

UNITED STATES PATENT OFFICE.

ANDREW J. BROOKINS, OF CHICAGO, ILLINOIS.

GOVERNOR FOR AUTOMATIC CONTROL APPARATUS FOR RAILROADS.

Application filed September 1, 1922. Serial No. 585,613.

To all whom it may concern:

Be it known that I, ANDREW J. BROOKINS, of Chicago, in the county of Cook and State of Illinois, and a citizen of the United States, 5 have invented certain new and useful Improvements in Governors for Automatic Control Apparatus for Railroads, of which the following, when taken in connection with the drawing accompanying and forming a 10 part hereof, is a specification.

This invention relates to ensure a predetermined pressure of air in the train pipe of an air brake system, and to apparatus to automatically control the speed of a train, 15 and has particular application to that class of devices the objects whereof are to control the movements of trains, and, where necessary, or advisable, to automatically bring the train to a stop, without human co-operation.

20 The invention assumes that when a given speed of a train is to be permitted a given pre-determined pressure must be maintained in the train pipe of the air brake system.

Among the objects of the invention is to 25 obtain an apparatus which, when the train is travelling at a determined rate of speed, will automatically give warning which must be observed, when a pre-determined train line pressure of the air brake system is diminished; to obtain an automatically operating apparatus by means of which excessive speed of a locomotive and train, (or motor), equipped therewith, is prevented; to obtain an apparatus to control low speed movements; and to obtain an apparatus of the 30 kind named which is simple in construction, comprising few parts, effective in operation, and which will automatically give warning when any essential operative part thereof is 35 broken or out of order.

40 In the drawing referred to the single figure is a vertical section of the apparatus embodying the invention, showing all movable and immovable parts, the movable parts being illustrated in normal position in full lines, and in abnormal position being indicated by broken lines, and showing an application of the apparatus on a truck wheel.

45 A reference character applied to designate a given part indicates said part throughout the several figures of the drawing wherever the same appears.

Referring to the drawing, A represents a

shaft, and A¹ a base which is rigidly secured to said shaft to turn therewith. Base A¹ is 55 secured to the driving member, (wheel X), by bolts in apertures a¹, a¹, which extend also into the driving member. A² represents a housing which is mounted on base A¹, by bolts in apertures a, a, of the housing and of 60 the base A¹, to turn therewith. A³ represents a raised table on base A¹, and is provided with a slot or transverse groove a³. B, B, represent levers which are pivotally mounted on base A¹, by pins b, b, and B¹, B¹, 65 represent weights on the free ends of levers B, B. B³ represents a collar which is connected to levers B, B, respectively, by connections B², B², which are respectively attached to said levers by pins b¹, b¹, and to 70 the collar by pins b², b². C, C, represent balls which are separated and retained by retainer C¹. C² represents a collar associated with said balls. D represents a movably mounted shaft, of hollow construction, which 75 acts as a bearing for shaft A, and D¹ represents a retaining collar which is co-actuable with balls C, C. Retainer C¹, collar C² and collar D¹ form a roller bearing in combination with the balls C, C, between the rotating 80 shaft A and the non-rotating hollow shaft D, said collar D¹ being rigidly secured to said shaft. D² represents a retaining member which is rigidly secured on the end of shaft D, and D³ a collar at one end of said retaining member. D⁴ represents a cup which forms an air retainer, and which is secured in position by the collar D³ being forced 85 against it by retaining member D². D⁵ represents a collar which fits between the cup D⁴ 90 and the shoulder D⁶ on shaft D, and serves, in combination with collar D³ to hold said cup rigidly in position on the shaft D. D⁷ represents an expansion ring to force the cylindrical wall of cup D⁴ against the inner 95 cylindrical wall of the bushing (E¹), in which it is mounted. E represents a cylindrical housing which is bored out to accommodate the bushing E¹. The walls of bushing E¹ form chambers which are positioned 100 respectively, above and below the cup D⁴, and are designated by the characters E², E³, E⁴, E⁵, E⁶, and E⁷, respectively represent passageways through the housing E, having ports communicating with chambers E², E³. 105 E⁸ represents a by pass from passageway E⁴

to chamber E^2 . E^9 represents a stuffing box to retain air in chamber E^2 , and E^{10} a stuffing box to retain air in chamber E^3 . E^{11} represents a head on the end of housing E secured thereto by bolts in apertures e, e . G represents a cap or cover which is secured to housing E , and G^1, G^1 , represent guides secured to cap or cover G , and extending in grooves G^2, G^2 , in member D^2 , to preclude the possibility of shaft D and its associated parts from revolving with shaft A . G^4 represents a collar which is secured to housing E by bolts in apertures e^4, e^4 , to hold the non-rotatable housing E in proper relative longitudinal position with the rotatable housing A^2 .

The apparatus illustrated is represented as mounted on one of the wheels X , in side elevation. T represents a device for automatically controlling air passages on a truck or motor car in response to signal conditions existing on the track in advance of said truck or motor car. S indicates the train line of an air brake system. The train control device T is indicated as being in connection with the train line S by conduit T^1 , and is connected to passage way E^5 of the apparatus embodying this invention by the conduit T^2 , and to passage way E^7 by conduit T^3 . S^1 indicates a conduit connecting train line S with passage way E^4 . E^6 is the exhaust passage way of the apparatus, and can be connected to other mechanisms for the automatic application of brakes, or it may discharge to the atmosphere, as illustrated.

The chamber E^2 is in communication with the train line S through passage way E^4 and its port when the cup D^4 is below, (as illustrated), the said port, and at all times by the by pass E^8 . The train control device T controls communication between the train line and passage ways E^5, E^7 . Should a condition exist that would cause the train control device to function to admit air from the train pipe into passage way E^7 , said air will flow into chamber E^3 , and said air will have a tendency to equalize the pressure on both sides of cup D^4 , (in chambers E^2 and E^3).

The operation of the apparatus is as follows; air being admitted into chamber E^2 , through the port of passage way E^4 , and conduit S^1 from the train pipe S , the pressure of said air on the cup D^4 , tends to hold said cup and associated parts in normal position, against the centrifugal force of the rotating shaft A , base A^1 , arms B and balls or weights B^1, B^1 . So long as the pressure of air in chamber E^2 corresponds with the pre-determined speed of rotation of shaft A , the cup D^4 and associated parts remain in normal position, but should said pressure of air in train pipe S and chamber E^2 , be diminished from what I term corresponding pressure, the weights B^1, B^1 , will be moved

by centrifugal force into substantially the position illustrated by full lines, and the cup D^4 will be moved into substantially the position illustrated by full lines, and the port of passage way E^4 will discharge into chamber E^3 , and flow from said chamber through the exhaust passage way E^6 , to apply the brakes. To permit the train or motor to proceed the speed of the train must be diminished until the centrifugal force of the weights B^1, B^1 , is insufficient to overcome the pressure of the air in chamber E^2 , admitted through by pass E^8 , and thereby permitting the cup D^4 and its associated parts to move to normal position again admitting air from conduit S^1 and the port of passage way E^4 , into chamber E^2 .

Should the train control device indicated by T function, to admit air from the train pipe S through conduit T^2 and the port of passage way E^7 , the pressure of the air in chambers E^2 and E^3 will be equalized, or nearly so, and the weights B^1, B^1 , will assume the position indicated by full lines, and the cup D^4 and associated parts will be moved to direct air from the port of passage way E^4 into chamber E^3 , and the brakes will be applied as before recited.

Should the train control device indicated by T function to admit air from the train pipe S through conduit T^3 and the port of passage way E^5 , (cup D^4 being positioned by the centrifugal force of levers B and weights B^1 so that said port and the port of outlet passage way E^6 are in chamber E^3) said air flows through said chamber and brakes are applied until the speed of the motor or truck is diminished so that the pressure of air in chamber E^2 moves said cup and associated parts to position so that the air from the said port of passage way E^7 is discharged into chamber E^2 , when the brakes will be released. So long as said diminished speed of the motor or truck is maintained the brakes are not applied and the motor or truck may proceed at said diminished speed.

In case of breaking or failure to function of any of the associated parts of the centrifugal generating mechanism, the pressure of air in chamber E^2 will force the cup D^4 into position in which the inlet port of passage way E^4 and the port of passage way E^6 are both in chamber E^2 , and the exhaust of air resulting will apply the brakes, thus giving notice of said failure to function.

In order to maintain the cup D^4 in position to have the port of passageway E^4 in chamber E^2 , and the port of outlet E^6 in chamber E^3 , the pressure of air in the train pipe and in chamber E^2 must be as pre-determined relative to the speed of rotation of levers B, B , and weights B^1, B^1 , so that said pressure and the centrifugal force generated shall substantially equalize, to hold the cup D^4 in its pre-determined position with said ports

on opposite sides thereof. Hence, if the pressure in the train pipe and in chamber E^2 diminishes notice thereof is automatically given, and before the train can proceed 5 without the application of the brakes, said pressure must be increased by the person in charge.

Relative to the movement of the air retainer D^4 , air under train pipe pressure in 10 chamber E^2 tends to yieldingly force said air retainer in what I term an advancing direction; and the centrifugal force generated by the revolution of shaft A , levers B , B , and weights B^1 , B^1 , tends to move said air retainer in what I term a retracting direction.

Air under train pipe pressure in the chamber E^2 forms what I term a power control element, as also, when admitted to chamber E^3 through the port of passage way E^7 , but 20 acting on the air retainer D^4 , in the opposite direction from the air in chamber E^2 .

I claim:

1. A rotatably mounted shaft, a non-rotatable hollow shaft longitudinally movable on 25 said rotatable shaft, means connecting said shafts so that centrifugal force generated by said connecting means tends to move said hollow shaft in a determined direction, in combination with a cylinder, a cup on said 30 hollow shaft arranged to form an air retainer, and to divide said cylinder into chambers, ports in said cylinder and passage ways to said ports, said ports controlled by said air retainer to determine the chamber 35 with which said ports are in communication.

2. A rotatably mounted shaft, a non-rotatable hollow shaft longitudinally movable on said rotatable shaft, means connecting said shafts so that centrifugal force generated 40 by said connecting means tends to move said hollow shaft in a determined direction, in combination with a cylinder, a cup on said hollow shaft arranged to form an air retainer, and to divide said cylinder 45 into chambers, ports in said cylinder, an exhaust passage way to one of said ports and inlet passage ways to the remainder of said ports, said ports controlled by said air retainer to determine the chamber with which 50 said ports are in communication.

3. A brake pipe, a cylinder provided with a plurality of chambers, a movable wall between said chambers, a connection between one of said chambers and said brake pipe in 55 combination with rotatably mounted means to move said wall in a determined direction, means to selectively connect said train pipe to the remaining one of said chambers, the selective connection of said brake pipe to said remaining chamber adapted to admit air under pressure to yieldingly force said movable wall in said determined direction.

4. A cylinder provided with a plurality of ports in spaced relation, a movably mounted air retaining member in said cyl-

inder arranged to selectively control communication between said ports, means comprising air under train pipe pressure adapted to yieldingly force said movably mounted member in a determined direction, in combination with rotatably mounted means adapted to move said movably mounted member in a counter direction. 70

5. A cylinder provided with a plurality of ports in spaced relation, a movably mounted member in said cylinder arranged to selectively control communication between said ports, means comprising air under train pipe pressure adapted to yieldingly force said movably mounted member in a determined direction, in combination with rotatably mounted means to move said movable member in a counter direction, said rotatably mounted means arranged to co-act with said means to yieldingly force, to suspend 80 said movably mounted member in a predetermined position. 75

6. A brake pipe containing air under pressure, a cylinder provided with an inlet port and an outlet port, a connection between said inlet port and said brake pipe, a movably mounted air retaining member in said cylinder, said pressure of said air adapted to yieldingly force said movably mounted member in a determined direction, in combination with means to generate centrifugal force, and a connection between said last named means and said movably mounted member. 90 95

7. A power control element, a cylinder provided with a plurality of ports in spaced relation, a movably mounted member in said cylinder, said member arranged to selectively control communication between said ports, and an additional port, in combination with rotatably mounted means to move said movably mounted member in a retracted direction, said rotatably mounted means arranged to co-act with said element to suspend said movably mounted member in a predetermined position, and arranged so that air under pressure from said additional port co-acts with said rotatably mounted means. 100 105 110

8. A power control element, a cylinder provided with a plurality of ports in spaced relation, a movable member in said cylinder, said member arranged to selectively control communication between said ports, said element adapted to yieldingly force said movable member in an advanced direction, in combination with rotatably mounted means to move said movable member in a retracted direction, said element, when directed in a determined port adapted to yieldingly force 115 said member in said retracted direction. 120

9. In a governor, a rotatably mounted member, a longitudinally movable member, a connecting means between said members, said rotatably mounted member adapted to 130

generate centrifugal force to move said longitudinally movable member in a retracted direction, in combination with a cylinder, a plurality of ports to said cylinder, 5 means to transmit air under pressure to said cylinder, said means comprising the braking system of a train, and said air in said cylinder adapted to move said longitudinally movable member in an advanced 10 direction.

10. A power control element, a cylinder provided with an inlet port and an outlet port, a movably mounted member in said cylinder arranged to control communication 15 between said ports, and said element adapted to yieldingly force said movably mounted member in an advanced direction, in combination with a rotatably mounted member adapted to move said movably mounted member in a retracted direction, and arranged to co-act with said element to suspend said movably mounted member in a predetermined position.

11. A brake pipe containing air under 25 pressure, a cylinder provided with an inlet port and an outlet port, a connection between said inlet port and said brake pipe, a movably mounted air retaining member in said cylinder, said pressure adapted to yieldingly force said movably mounted member in a determined direction, in combination with means arranged to co-act with said pressure to suspend said movably mounted member in a predetermined position.

12. A brake pipe containing air under 30 pressure, a cylinder provided with an inlet port and with an outlet port, a connection between said inlet port and said brake pipe, a movably mounted air retaining member in 35 said cylinder adapted to control communication between said ports, said pressure adapted to yieldingly force said movably mounted member in a determined direction, in combination with means to suspend said movably mounted member in a predetermined position.

13. A brake pipe containing air under 40 pressure, a cylinder provided with a plurality of ports in spaced relation, a movably mounted wall in said cylinder arranged to form chambers, said wall arranged to selectively control communication between said ports, said pressure in one of said chambers from one of said ports adapted to yieldingly force said wall in an advanced direction, in combination with rotatably mounted means to co-act with said pressure to suspend said wall, said means arranged to move said wall in a retracted direction, and said pressure in one of said chambers from a determined port adapted to yieldingly force said member in said retracted direction.

14. A brake pipe containing air under 45 pressure, a cylinder provided with an ad-

vanced inlet, an intermediate inlet, a low inlet, and an outlet, a connection between said brake pipe and said advanced inlet, in combination with a movably mounted member adapted to be yieldingly forced in an advanced direction by pressure in said cylinder from said advanced inlet, rotatably mounted means to move said movable member in a retracted direction, said movable mounted member adapted to selectively control communication between inlets and said outlet, on a determined movement in said retracted direction.

15. A cylinder provided with a main port, an intermediate port, a low speed port and 50 an exhaust port, a brake pipe containing air under pressure connecting with said main port, in combination with a movably mounted member in said cylinder, said pressure through said main port adapted to yieldingly force said movably mounted member in an advanced direction, means to move said movably mounted member in a retracted direction, said movably mounted member arranged to selectively establish communication between said inlet ports and said exhaust ports on a determined movement thereof in a retracted direction.

16. A cylinder provided with a chamber and an additional chamber, an outlet to said cylinder, a movably mounted member adapted to control communication between said chambers and said outlet, in combination with a brake pipe containing air under 55 pressure, a means to connect said first chamber with said brake pipe, said pressure in said first chamber adapted to yieldingly force said movable member in an advanced direction, and said pressure in said additional chamber adapted to yieldingly force said movable member in a retracted direction, said movable member arranged to establish communication between said additional chamber and said outlet on a determined movement thereof in said retracted direction.

17. A brake pipe under pressure, a cylinder provided with an inlet port, an additional inlet port and an outlet port, a connection between said inlet port and said brake pipe, in combination with a movably mounted member adapted to control communication between said ports, means to move said movably mounted member in a retracted direction, said pressure in said cylinder from said additional port adapted to yieldingly force said movably mounted member in said retracted direction and said movably mounted member arranged to establish communication between said additional port and said outlet port on a determined movement in said retracted direction.

18. A brake pipe containing air under pressure, a cylinder provided with an inlet port and an outlet port, a connection between said inlet port and said brake pipe, a

movably mounted air retaining member in said cylinder, said pressure adapted to yieldingly force said movably mounted member in an advanced direction, in combination with means to suspend said movably mounted member in a determined position, said means to suspend comprising a rotatably mounted member adapted to move said movably mounted member in a retracted direction.
